UNITED STATES PATENT OFFICE.

JEROME H. HENNESSEY, OF WASHINGTON, DISTRICT OF COLUMBIA.

PROCESS OF MAKING INKING-ROLLERS.

No. 905,182.

Specification of Letters Patent.

Patented Dec. 1, 1908.

Application filed October 15, 1907. Serial No. 397,493.

To all whom it may concern:

Be it known that I, JEROME H. HENNESSEY, a citizen of the United States, residing at Washington, in the District of Columbia, 5 have invented certain new and useful Improvements in Processes of Making Inking-Rollers, of which the following is a specification.

This invention especially relates to the 10 manufacture of the ductor-rollers which are employed in printing-presses to transfer ink from the fountain-roller to the distributer-plate or roller. These ductor-rollers usually consist of a cylindrical metal core or body 15 having journals, upon which is a concentric cast layer of a composition of glue and glycerin. In printing heavy forms it is necessary to supply a thick layer of ink to the distributer-plate or roller and to decrease the 20 supply of ink for light forms. This result is commonly effected by a series of adjusting screws acting on a flexible strip to vary the thickness of the layer of ink supplied to the rollers. A change from a heavy to a light 25 form or the reverse requires a careful adjustment of each of these fountain-screws.

The present invention is a process of making an inking-roller having an elastic cast body with a helical ink-receiving surface. 30 By providing a printing-press with interchangeable ductor-rollers having helical surfaces of different area, the amount of ink delivered from the fountain to the distributer may be varied without adjusting the fountain-screws, by merely substituting a roller with a smaller surface when it is desired to change from a heavy to a light form. That 35 is, each of the ductor-rollers is supplied by the fountain-roller with an ink-layer of uniform thickness but the area of this layer varies, depending on the receiving surface of the ductor-roller. The present invention is 40 a process of making these rollers, by helically winding a core with a flexible strip, placing the wound core in a tubular mold with the outer surface of the strip in contact with the mold-wall, casting the composition onto the core and into the spaces between the strip, removing the wound core and casting, and 45 50 unwinding the strip.

Referring to the accompanying drawings: Figure 1 is a vertical axial section of the roller-mold with the core and wound strip therein, in position for casting; Fig. 2 is a 55 side elevation of an inking-roller cast in the

mold of Fig. 1, the flexible strip having been removed; and Fig. 3 is a side elevation of a portion of a modified roller, the ink-receiving surface of which comprises right and left-hand narrow helices.

In order to cast the roller, a cylindrical metal core 1 is helically wound with a flexible strip 2 which may be of leather, the ends of this strip being secured for example by pins 3 passing transversely through holes in these ends and through corresponding transverse holes in the upper and lower ends of the core. The wound core is then inserted in the tubular mold 4, with the surfaces of the strip substantially in contact with the inner wall of the mold. The mold is then placed in position for casting, its lower journal 5 being supported in a central seat in the mold-base 6 and its upper journal 7 being centered by a removable spider 8. 70 The composition, for example a mixture of glue and glycerin, is then forced into the base of the mold through the pipe 9 and fills the spaces between the wound strip. When the composition solidifies, the wound 80 core and casting are removed from the mold, the strip is unwound and the ends of the casting are trimmed off, the resulting elastic cast body 10 having the shape shown in Fig. 2, that is having a relatively narrow helical 85 ink-receiving surface.

The inking-roller shown in Fig. 3 has a cast elastic body 10', with an ink-receiving surface 11 comprising two narrow right and left-hand helices, meeting at the middle of 90 the roller. This roller is made by the same process as that shown in Fig. 2, two flexible strips of suitable form to cast the groove between the helices being wound on the core, in a right and left-hand direction respectively, from the middle to the ends of the core.

I claim:

1. The process of making an inking-roller, which consists in helically winding a core 100 with a flexible strip, placing the wound core in a tubular mold with the outer surface of the strip substantially in contact with the mold-wall, casting roller-composition onto the core and into the spaces between the strip, removing the wound core and casting, and unwinding the strip.

2. The process of making an inking-roller, which consists in helically winding a core 105 with a flexible strip, placing the wound core 110

in a tubular mold with the outer surface of the strip substantially in contact with the mold-wall, forcing roller-composition upward into the mold and causing it to fill 5 the spaces between the strip, removing the wound core and casting, and unwinding the strip.

In testimony whereof, I affix my signature in presence of two witnesses.

JEROME H. HENNESSEY.
